UNITED STATES PATENT OFFICE.

MILTON V. TUCKER, OF HAZLEWOOD, KENTUCKY.

HARVESTER-REEL.

SPECIFICATION forming part of Letters Patent No. 718,038, dated January 6, 1903.

Application filed September 2, 1902. Serial No. 121,798. (No model.)

To all whom it may concern:

Be it known that I, MILTON V. TUCKER, a citizen of the United States, residing at Hazlewood, in the county of Ballard and State of Kentucky, have invented certain new and useful Improvements in Harvester-Reels; and I do declare the following to be a full, clear, and exact description of the invention, such as will enable others skilled in the art 5 to which it appertains to make and use the same.

This invention relates to improvements in folding harvester-reels, the object being to provide a device of this character which when 15 not in use may be quickly, easily, and compactly folded into a small space and readily unfolded again for use, a further object being to produce such a device which shall be simple in construction, durable in use, inexpensive, and well adapted to the use for which 20 it is designed.

With these and other objects in view the invention consists in the novel construction and combination of parts, as will be herein- 25 after more fully described and claimed, reference being had to the accompanying drawings, in which—

Figure 1 is an end elevation of the reel, showing the parts unfolded or in operative position. Fig. 2 is a similar view showing the parts folded. Fig. 3 is a longitudinal vertical section of the reel with the parts unfolded. Fig. 4 is a side view of the same with the parts folded; and Fig. 5 is a detail transverse sectional view through the shaft, hub, and inner 35 ends of the arms, showing the position of the parts as in Fig. 1.

In the drawings, 1 denotes the ordinary reel-shaft of a harvester, which may be supported 40 by and geared up to the machine in the ordinary manner.

2 denotes the folding-reel, comprising a central hub consisting of the circular plates 3, fixed upon the end of the shaft 1 and held together and spaced apart by means of a rivet 4, passing through a sleeve 5, located between the plates 3, as shown.

6 denotes the radially-disposed arms of the reel, which are hinged together at their inner 45 ends, the said inner ends being adapted to lie between the plates 3 when the reel is in an unfolded or opened position, one of said arms

6^a being rigidly connected to the plates by means of a rivet or bolt being passed therethrough and through the arm. 55

7 denotes a flat metal ring concentrically disposed around the hub and adapted to pass through an elongated slot 8, formed in each arm 6, the arm 6^a having a rigid connection with the ring 7, whereby said ring is held in 60 concentric relation to the hub.

9 denotes a series of apertures formed around the ring 7 equidistant apart, and 10 denotes apertures formed in the arms 6, which when the reel is unfolded are adapted to register with the openings 9 in the ring 7, and 12 denotes spring-actuated detents carried by the arms 6 and which are adapted to engage the holes 10 in the arms 6, and when said holes are brought into alignment with the holes 9 70 in the ring the detent 12 will spring into said holes 9 and securely lock the arms 6 to the ring 7.

13 denotes the cross bars or blades of the reel, each of which is provided midway its 75 ends with a metal strap or ferrule 14, having a depending lug or ear which is adapted to engage a slot formed in the end of each of the arms 6 and to be pivoted thereto by a pin or bolt 15, thereby allowing the blades 13 to be 80 folded up against the arms 6.

16 denotes segmental-shaped metal braces connected at their ends to the blades on either side of the center thereof and adapted to pass through a slot in the arms 6. The segments 16 are each provided with a centrally-disposed aperture 17, which when the blades are unfolded or opened will register with openings 18, formed in the arms 6. 85

19 denotes spring-actuated detents connected to the arms 6 and are adapted to engage the openings 18, formed therein, and when the blades are opened the engaging end of the detent will spring into the opening 17, formed in the segmental braces, thereby securely locking the blades in their open or unfolded position. 90

The reel may be provided with any desired number of movable arms 6, arranged on each side of the fixed arm 6^a, the two arms adjacent to the said fixed arm being hinged thereto and each consecutive arm being hinged to the one before it, except the last two, which are not connected together, thereby allowing 100

the hinged arms to fold up on each side of the fixed arm, as shown in Fig. 4 of the drawings.

In order to fold the reel, the spring-detents 5 19 are released from engagement with the segments 16, and the blades are then folded down alongside the arms 6. The detents 12 are now released from engagement with the openings in the ring 7, and the arms 6 are folded 10 together and up against the fixed arm 6^a.

When the parts are in their folded position, the harvester may be moved over rough roads without danger of racking the reel and often breaking the parts. Also when so folded 15 the reel occupies comparatively small space, thereby saving storage room in the barn. Furthermore, a reel constructed as described requires considerably less material than is used on reels of the ordinary construction.

20 From the foregoing description, taken in connection with the accompanying drawings, various changes in the form, proportion, and minor details of construction may be made without departing from the principle or sacrificing any of the advantages thereof.

Having thus particularly described my invention, what I claim, and desire to secure by Letters Patent, is—

1. In a harvester-reel the combination with 30 a hub, an arm fixed to said hub, movable arms hinged to said fixed arm and to each other, a supporting-ring rigidly connected to said fixed arm and passing through said movable arms,

means for locking said movable arms to said ring, cross bars or blades pivotally connected to the outer ends of the arms, segmental braces fixed to said blades and adapted to be locked to said arms to hold said blades in an operative position and means for locking said segmental braces to said arms, substantially 40 as shown and described.

2. In a harvester-reel the combination with a supporting hub and ring, of an arm fixed to said hub and ring, movable arms hinged to each side of said fixed arm and to each other 45 and adapted to move on said supporting-ring to fold together, spring-actuated detents for locking said arms to said ring, cross bars or blades pivotally connected to the outer ends of said arms, segmental braces fixed to said 50 blades to hold the same at right angles to the arms, and adapted to be moved in an arc of a circle through a slot in said arms to fold said blades alongside said arms, and spring-actuated detents for locking said segmental 55 braces to said arms, when the blades are at right angles thereto, substantially as shown and described.

In testimony whereof I have hereunto set my hand in presence of two subscribing witnesses.

MILTON V. TUCKER.
